UNITED STATES PATENT OFFICE.

RENÉ COZETTE, OF COURBEVOIE, FRANCE.

CARBURETOR.

Application filed June 30, 1920. Serial No. 393,080.

(GRANTED UNDER THE PROVISIONS OF THE ACT OF MARCH 3, 1921, 41 STAT. L., 1313.)

To all whom it may concern:

Be it known that I, RENÉ COZETTE, a citizen of the French Republic, and resident of 38 Rue Victor Hugo, Courbevoie, Seine, France, have invented certain new and useful Improvements in Carburetors (for which I have filed an application in France October 29, 1915, Patent No. 524,811, May 20, 1921), of which the following is a specification.

The present invention relates to a carburetor for internal combustion engines the essential characteristic feature of the invention being the combination of two nozzles the discharge of fuel from one of which at different speeds of the motor or engine is compensated by an inversely proportional increase in the supply of fuel from the other nozzle the result being that the two nozzles 20 always supply a suitable percentage of fuel in accordance with the requirements of the engine or motor.

In the present carburetor the main nozzle feeds in proportion to the suction and is adjusted so that it ensures by itself the fuel necessary for high engine or motor speed, the auxiliary nozzle at this time being more or less inoperative or delivering very little if any fuel. On the contrary when the engine or motor speed decreases, or when under the effect of increased load or from any other cause, the speed of the engine or motor decreases the fuel feed from the main nozzle becomes very slight in order 30 to give normal carburation, the auxiliary nozzle then becomes automatically operative to compensate for the defective fuel feed from the main nozzle. At lower speeds the feed from the main nozzle is almost nil, 40 whilst the auxiliary nozzle feeds almost the entire amount of fuel necessary for carburation. In other words the auxiliary nozzle acts as a compensating device for the supply of fuel which supply is inversely proportional to that of the main nozzle.

A constructional form of carburetor complying with these conditions is illustrated by way of example in the accompanying drawing which shows a vertical longitudinal section of a carburetor in accordance with the present invention.

Referring to the drawing the carburetor comprises two nozzles 1, 2 disposed concentrically with and at the centre of the

mixing tube 3, its main nozzle 2 communicating directly with a feed passage 4 delivering liquid fuel from a constant level float chamber 5, whilst the auxiliary nozzle 1 is supplied by a branch passage 6 fed with liquid fuel from an intermediate chamber 7.

The chamber 7 communicates by a tube 8 provided with a number of staggeredly arranged holes 9, with the main feed passage 4. A cap 10 having a central air vent 10^a is provided so as to close the tube 8 but still allow of communication of the tube 8 with the atmosphere. The chamber 7 is itself in communication with the atmosphere through the space between the cap 10 and the wall of the chamber, so that the liquid in the chamber 7 and the tube 8 always tends to stand at the same level.

The removable plug 11 provided with an opening of definite section, is disposed in the feed passage 4 at a point where the latter is branched from the float chamber 5. This calibrated plug 11 has for its object to produce a resistance to the escape of the liquid and consequently to create a depression in the feed passage 4 thereby lowering the level of the liquid fuel in the tube 8 relatively to the float chamber 5 under certain conditions of operation of the carburetor.

The calibrated opening in the plug 11 is chosen for a motor or engine of definite power so that when the motor or engine rotates at its maximum speed the level of the liquid fuel in the tube 8 is adjacent to the bottom part of the said tube, the level of the liquid fuel tending to rise in the tube 8 as the speed of the engine or motor decreases.

The action is as follows:

When the motor or engine rotates at high speed the suction produced in the mixing tube 3 determines the amount of liquid discharged from the main nozzle 2. During this discharge suction is exerted on the auxiliary nozzle 1 which since the motor is rotating at high speed withdraws a part of the liquid fuel contained in the annular space, the chamber 7 and the tube 8 so that the level of the liquid fuel falls towards the lower part of the tube 8 but does not fall so low as to permit air to enter the branch passage 6.

When the speed of the motor or engine decreases from any cause whatsoever the suction effect is obviously reduced and the feed from the main nozzle accordingly decreases, resulting in a decrease in the speed at which the liquid fuel escapes into the passage 4 and consequently the liquid fuel rises in the tube 8 and passes through the holes 9 therein into the chamber 7 the number of holes immersed gradually increasing as the liquid rises in the tube. The holes 9 therefore form so many nozzles the passage of fuel through which during action is dependent on the height of the level of the liquid fuel in the tube 8. In some conditions such as when the level falls in the tube 8 under the effort of increased motor or engine speed a certain number of the holes cease to feed, thereby diminishing the total feed from the auxiliary nozzle 1, thus correcting and compensating inversely and automatically the increased feed from the main nozzle 2 which feed would tend to become excessive. On the contrary when the speed of the motor or engine decreases, the supply from the nozzle 2 accordingly decreases and would not supply a sufficient quantity of liquid fuel. The liquid fuel then rises in the tube 8 in consequence of the decreased suction effect in the passage 4, a certain number of holes 9 being thus covered by the body of liquid fuel rising in the tube 8 and ready for feeding thereby increasing the supply or feed from the auxiliary nozzle which corrects and compensates for the defective carburation from the main nozzle.

A carburetor as hereinbefore described always permits of a considerable percentage of the liquid fuel in the carburetted mixture, whatever may be the motor or engine speed. Further its application is easy because, the desired carburation for each motor or engine can be obtained in accordance with its speed by increasing or decreasing the number or the diameter of the holes in the tube 8, immediately below the line of level decided on for any particular speed of the motor.

In particular, the richness of the mixture can be increased or decreased for low motor or engine speeds in order to avoid the phenomena known as "hang-fire" which is produced in the induction pipes when the column of induced mixture is throttled in the carburetor, resulting in decreasing the compression in the motor or engine.

The construction and arrangement here-

inbefore described, the forms, dimensions, details of execution and applications may be varied without departing from the nature of the invention.

For example the two nozzles instead of being disposed concentrically could be spaced apart on two parallel or convergent axes and in the same pipe for the formation of the mixture.

Having now particularly described and ascertained the nature of my invention and in what manner the same is to be performed I declare that what I claim is:

1. In a carburetor, a mixing chamber, main and compensating nozzles arranged in the mixing chamber, a constant level fuel reservoir, a variable level fuel reservoir, a duct connecting the main nozzle with the constant level reservoir and the variable level reservoir, the latter being open to the atmosphere and being connected with the compensating nozzle, means for controlling the discharge of liquid fuel from the constant level reservoir, the connection between the compensating nozzle and the variable level reservoir having a variable cross sectional area.

2. In a carburetor, a mixing chamber, main and compensating nozzles arranged in the mixing chamber, a constant level reservoir, a variable level reservoir, a duct connecting the main nozzle with the constant level reservoir and the variable level reservoir, said variable level reservoir being open to the atmosphere and communicating with said duct and with the compensating nozzle, means for controlling the discharge of liquid fuel from the constant level reservoir, and means for controlling the supply of liquid fuel to the compensating nozzle according to the height of the column of liquid standing in the variable level reservoir.

3. A carburetor in accordance with claim 1 characterizing that the variable level reservoir of the compensating nozzle comprises an annular space defined between a vertical cylindrical cavity and an internal tube concentric therewith, said annular space communicating with the compensating nozzle and the lower part of the tube being connected to the duct of the main nozzle and being provided with stepped openings which, according to the number thereof immersed in the liquid fuel, control the flow of fuel to the compensating nozzle.

RENÉ COZETTE.
